UNITED STATES PATENT OFFICE.

DELBERT KNAPP, OF CEDAR RAPIDS, IOWA.

STORAGE STRUCTURE.

Application filed June 27, 1921. Serial No. 480,893.

To all whom it may concern:

Be it known that I, DELBERT KNAPP, a citizen of the United States, residing at Cedar Rapids, in the county of Linn and 5 State of Iowa, have invented certain new and useful Improvements in Storage Structures; and I do hereby declare the following to be a full, clear, and exact description of the invention, such as will enable others 10 skilled in the art to which it appertains to make and use the same.

This invention relates to the storage of bulky commodities, such as coal, for example, and the object of the invention is to 15 provide an improved structure adapted for the convenient storage of such commodities, especially coal, in different sorts, and in large quantities in a limited floor space.

The invention is fully disclosed in the 20 description and claims following, reference being had to the accompanying drawings, in which:—

Fig. 1 is a plan view of a storage structure embodying my invention. Fig. 2 is a section 25 of the same on the line 2—2 of Fig. 1. Fig. 3 is a fragmentary section on the line 3—3 through the intermediate filling chute here- 30 after to be described. Fig. 4 is a section on the same line at the lower end of the same part of the structure.

In the drawing the numeral 5 denotes the outer rail of a spur-track. At the lawful 35 distance therefrom is set the storage structure. This, in practice, is preferably composed of five bins 6 disposed on three sides of an area-way 7, open to the track. In this area-way is sunk a pit 8 of sufficient depth to allow the coal from the adjacent bins to flow by gravity into a large hoisting 40 bucket 9, which is supposed to be operated by power, not shown, connecting with a cable 10 connecting with a cross-bar 11 running on vertical guides 12, like an ordinary elevator. All of the adjacent bins communicate 45 with the pit by radiating, inclined chutes 13 and 14, a portable chute 15 being used to carry the coal from the bin-chutes to the elevating bucket, as shown in Fig. 2. The floors of the various bins are inclined 50 to the chutes, as shown by the shading, and as indicated by dotted lines in Fig. 2. The coal may thus flow by gravity from the bins to the elevator in reclaiming the material, and all shoveling, or practically all, be 55 dispensed with.

The bins are composed of horizontal

planks 16 secured to posts 17, external to the bins, and thinner posts 18 set on both sides of the partitions between two bins. The walls are bound firmly together by diagonal steel braces 19 bolted to the walls and through the posts across the corners. In practice these are set about three feet apart vertically, and bind the bins against bulging, and without interfering with the 60 65 contents.

To economize floor-space the bins are run up as high as circumstances require, those herein shown being in a scale of about thirty feet in height. As the dumping of 70 coal over the top by means of portable chutes, and permitting it to fall the full depth would tend to break it up injuriously, provision is made for shortening the drop of the coal, as discharged from the elevator. 75 Portholes 20 in the walls opening on the court, are inwardly hooded at 21, and may thus receive the coal at any desired level, the higher ones being used successively as the bins fill. These are shown at 22 provided with 80 bar-screens, which riddle out the fine stuff, and allow the larger coal to pass into the bins. Receptacles for these screenings are provided below the screens by diagonal partitions or walls 23 in the corners of the court. 85 These are provided with suitable bottoms 24 above the main delivery chutes. The openings 25 are closed by suitable sliding gates 26, operable by hand-levers 27. Separate gates 28 for the main chutes may connect 90 with the same levers by the use of longer link connections, which are so simple as to need no description or illustration.

This arrangement and construction is such as to permit the storing and reclaiming of coal, and other materials, by the use, almost exclusively, of machinery, and this of a simple character, and without complicated or superfluous movements.

The elevator moves simply up and down, 100 no lateral movement being required. The material as transferred from the car is carried straight up to the desired level, and discharged by gravity, over a suitable chute, to its appropriate bin. The port-holes to 105 the different bins are disposed at such levels as to cause little breakage and but a moderate amount of dust, the small stuff being caught in separate compartments whence it may be removed as occasion demands. In 110 reclaiming the material for distribution the operations are equally simple and rapid.

The elevator being lowered into the pit, a chute carries the stored material to the elevator, on the lifting of any desired gate, and being elevated, it is discharged into wagons, 5 trucks or cars in the same manner as in the filling of the bins.

In practice the floors of the bins are preferably of concrete construction. The novel construction of the walls, however, makes 10 it practicable to use wood in their erection, and secure adequate strength, at very much less expense than would be required for a metal, or a reinforced concrete structure.

The construction is such that no other 15 fastening of the walls at the corners is needed than the bolting of the sections together through the connecting tie-bars. This is sometimes of great advantage, and especially when the location of the bins must 20 be changed, since it is possible to unbolt the structure, and with a derrick load the walls bodily on heavy trucks and transport them to the new site, where they may be re-assembled with little loss of time.

25 Having thus described my invention, I claim:

1. A storage-group consisting of continuous rectangular bins adjacent to an open court on three sides, and provided with receiving port-holes at a level intermediate 30 between the floor and top, the diagonal bins being accessible by chutes disposed corner-wise of said bins.

2. A storage-group composed of five similar, rectangular bins, enclosing an open court on three sides, and provided with filling port-holes at various levels, the port-holes for the corner bins communicating

40 with said bins through diagonal passageways.

3. A storage-bin composed of vertical supporting posts, transversely disposed planking attached thereto, internal tie-braces connecting the posts across the corners, 45 downwardly inclined floors and a discharging chute joining said floors along lines which are downwardly inclined.

4. A storage system, comprising a group 50 of storage-bins disposed around a court open on one side, and provided with discharging floors and chutes inclined downwardly toward the court, a pit in the court communicating with said chutes, and hoisting apparatus adapted to sink into the pit below 55 the level of the chutes, and receive the discharge therefrom by gravity.

5. A storage system, comprising a group 60 of rectangular bins disposed about an open court and provided with port-holes for filling from the court, inclined chutes leading from the floors of said bins, slideable gates therefor, a pit into which said chutes open, and hoisting apparatus adapted to sink into the pit below the outlet level of the chutes.

6. A group of storage bins disposed about 65 an open court and having filling-ports in the interior walls, screens inclining from the ports into the bins, and enclosures separate from the bins disposed below said screens.

70 In testimony whereof I affix my signature in presence of two witnesses.

DELBERT KNAPP.
